DESIGN FOR A FAN PROPELLER

Francesco G. Collura, New York, N. Y., assignor
to The Torrington Manufacturing Co., Torring-
ton, Conn., a corporation of Connecticut

Application November 14, 1941, Serial No. 104,147

Term of patent 14 years

To all whom it may concern:

Be it known that I, Francesco G. Collura, a citizen of the United States, residing in the city of New York, county of New York and State of New York, have invented a new, original, and ornamental Design for a Fan Propeller, of which the following is a specification, reference being had to the accompanying drawing, forming a part thereof.

In the drawing: Fig. 1 is a front elevational view of a fan propeller showing my new design;

Fig. 2 is a side elevational view of the fan pro-
peller shown by Fig. 1; Fig. 3 is a sectional view
taken along line 3—3 of Fig. 1; Fig. 4 is a sec-
tional view taken along line 4—4 of Fig. 1, and
Fig. 5 is a sectional view taken along line 5—5
of Fig. 1.

I claim:

The ornamental design for a fan propeller,
substantially as shown.

FRANCESCO G. COLLURA.
